UNITED STATES PATENT OFFICE.

WILLIAM DATTELBAUM, OF NEW YORK, N. Y.

DESIGN FOR A SETTING FOR FINGER-RINGS.

SPECIFICATION forming part of Design No. 16,722, dated June 8, 1886.

Application filed March 12, 1886. Serial No. 195,043. Term of patent 3½ years.

To all whom it may concern:

Be it known that I, WILLIAM DATTELBAUM, of the city, county, and State of New York, have invented a new and original Design for Settings for Finger-Rings, of which the following is a description.

Reference is to be had to the accompanying drawings, forming a part of this specification, in which similar letters of reference indicate corresponding parts in all the figures.

Figure 1 is a perspective view of a finger-ring, enlarged, to which my newly-designed setting has been applied. Fig. 2 is a face view of the setting. Fig. 3 is a face view of the setting shown with parallel sides. Fig. 4 is a face view of the setting shown with curved sides.

The leading feature of the design consists of a ring-setting having its entire top surface ornamented by corrugations, which corrugations are of different form and arranged in alternate series.

In the top of the setting A are alternately arranged series of corrugations B, of different form, which may vary in size and may extend 25 fully across the top or partly across the said top without departing from my design. The sides C of the setting A are plain, as illustrated in the drawings.

I claim—

The design for finger-ring settings herein shown and described, consisting in the setting A, having its top surface ornamented by groups, B, of corrugations, the corrugations in one group extending partially across said top 35 surface and those of the alternate groups extending entirely across.

WILLIAM DATTELBAUM.
